UNITED STATES PATENT OFFICE

98,861

DESIGN FOR AN EQUIPMENT CABINET

Raymond M. Harper, Los Angeles, Calif., assignor
to Union Oil Company of California, Los Angeles, Calif., a corporation of California

Application December 10, 1935, Serial No. 59,998

Term of patent 14 years

To all whom it may concern:

Be it known that I, Raymond M. Harper, a citizen of the United States and residing at 812 North Mariposa Avenue, in the city and county of Los Angeles, State of California, have invented a new, original, and ornamental Design for an Equipment Cabinet, of which the following is a specification, reference being had to the drawing, forming a part thereof.

In the drawing:

Figure 1 is a front elevational view of the equipment cabinet showing my design;

Figure 2 is a side elevational view of said cabinet.

I claim:

The ornamental design for an equipment cabinet, substantially as shown.

In witness whereof I affix my signature.

RAYMOND M. HARPER.
